(57) **CLAIM**

The ornamental design for a diffuser for essential oils as shown and described.

DESCRIPTION

FIG. 1 is a perspective view of an embodiment of a diffuser for essential oils according to the new design;

FIG. 2 is a front elevation view thereof;

FIG. 3 is a back elevation view thereof;

FIG. 4 is a right side elevation view thereof;

FIG. 5 is a left side elevation view thereof;

FIG. 6 is a top plan view thereof;

FIG. 7 is a bottom plan view thereof;

FIG. 8 is a perspective view of an embodiment of a diffuser for essential oils according to the new design;

FIG. 9 is a front elevation view thereof;

FIG. 10 is a back elevation view thereof;

FIG. 11 is a right side elevation view thereof;

FIG. 12 is a left side elevation view thereof;

FIG. 13 is a top plan view thereof; and

FIG. 14 is a bottom plan view thereof.

FIG. 15 is a perspective view of an embodiment of a diffuser for essential oils according to the new design;

FIG. 16 is a front elevation view thereof;

FIG. 17 is a back elevation view thereof;

FIG. 18 is a right side elevation view thereof;

FIG. 19 is a left side elevation view thereof;

FIG. 20 is a top plan view thereof; and

FIG. 21 is a bottom plan view thereof.

FIG. 22 is a perspective view of an embodiment of a diffuser for essential oils according to the new design;

FIG. 23 is a front elevation view thereof;

FIG. 24 is a back elevation view thereof;

FIG. 25 is a right side elevation view thereof;

FIG. 26 is a left side elevation view thereof;

FIG. 27 is a top plan view thereof; and

FIG. 28 is a bottom plan view thereof.

FIG. 29 is a perspective view of an embodiment of a diffuser for essential oils according to the new design;

FIG. 30 is a front elevation view thereof;

FIG. 31 is a back elevation view thereof;

FIG. 32 is a right side elevation view thereof;

FIG. 33 is a left side elevation view thereof;

FIG. 34 is a top plan view thereof; and,

FIG. 35 is a bottom plan view thereof.

The broken lines in the drawings indicate portions of the diffuser for essential oils that form no part of the claimed design.

The pairs of wavy dashed lines represent symbolic breaks showing indeterminate length, where the appearance of any

(Continued)

portion of the diffuser for essential oils between the lines forms no part of the claimed design.
